VELOCIPED

Norman G. Wintermantel, Palos Heights, and Clifford H. Bessett, South Holland, Ill., assignors to American Machine and Foundry Company, a corporation of New Jersey

Application March 26, 1957, Serial No. 45,449

Term of patent 14 years

(Cl. D34—15)

Fig. 1 is a side elevational view of a velocipede, showing our new design the opposite side having substantially the same appearance.

Fig. 2 is a rear perspective view thereof, a portion of the broken line showing being omitted for convenience of illustration.

The dominant features of our new design are shown in solid lines.

We claim:

The ornamental design for a velocipede, as shown and described.
